ELECTRONIC BURNER CONTROL
APPARATUS

Myron R. Smith, Minneapolis, and Harvey J. Smith, St. Louis Park, Minn., assignors to Minneapolis-Honeywell Regulator Company, Minneapolis, Minn., a corporation of Delaware

Application December 27, 1949, Serial No. 135,122

10 Claims. (Cl. 158—28)

1

The present invention is concerned with an automatic controller for a fuel burner and more particularly with that type of control which utilizes electronic circuits in its controlling function.

In certain types of fuel burner installations, particularly those employing a fuel which is highly explosive, it is necessary to provide controls which will respond quickly to any condition which will be dangerous if allowed to continue. By providing electronic flame detection in control circuits, the speed of response to dangerous conditions may be maintained at a high value and may be readily adjusted to suit the particular installation. When such electronic circuits are utilized it is also necessary to insure that operation of the burner will be prevented if the control is not functioning properly. Further, the control circuits must be so arranged that during off periods of the control burner, the control circuits will not accumulate any charges which might adversely affect operation upon a subsequent demand for burner operation. Another item of importance in such a control as the present one is the simplicity of design and the obtaining of a low voltage switching circuit so that an ordinary control thermostat may be utilized for initiating operation of the control.

It is therefore an object of the present invention to provide a new and improved electronic burner control.

A further object of the present invention is to provide a new and improved burner control utilizing an impedance timing circuit for shutting down the control burner upon a flame failure.

Still another object of the present invention is to provide a new and improved electronic burner control having a low voltage switching control circuit.

A still further object of the present invention is to provide an improved burner control where the control apparatus will maintain the burner inoperative if there is a flame failure or a false indication of flame.

Still another object of the present invention is to provide a condition control apparatus having a pair of transformers, one of which is continuously energized from a source of power and the other of which is arranged to be energized by said one transformer upon a need for operation of a condition changing means.

These and other objects of the present invention will be obvious upon a consideration of the accompanying specification, drawings and appended claims.

2

In the single figure, it will be noted that there is provided a thermostatic device 10 for controlling the flow of fuel to a fuel burner 11. The thermostat device 10 acting with the control circuits of the present invention locate in a housing 8 will initiate burner operation by energizing an electromagnetic pilot valve 12, an ignition transformer 13, and a main valve 14 after a pilot flame appears on the pilot nozzle 15 and impinges on a flame electrode 16. The complete operation of the apparatus in conjunction with the control fuel burner will be considered after considering the components included within the housing 8.

Supplying power to the control apparatus are 15 a pair of input power lines 20 and 21 connected to a primary 23 of a transformer 22. The transformer 22 has a pair of secondary windings 24 and 25, the latter of which is tapped at 26. The secondary 24 has a relatively low voltage thereon and is used for supplying an energizing voltage to the filament heaters 31, 32, 33 and 34. Each of these filament heaters is associated with a different one of the electron discharge devices of the present apparatus.

25 The secondary winding 25 is connected to the flame detection circuit of the present apparatus. Included in the flame detection portion of the apparatus are a pair of electron discharge devices 40 and 45 which may be separate sections 30 of a dual triode tube. The discharge device 40 comprises an anode 41, a control electrode 42, and a cathode 43. The discharge device 45 comprises an anode 46, a control electrode 47, and a cathode 48. The cathodes 43 and 48 are adapted to be heated by a pair of the filamentary heaters 31—34 energized by the secondary 24.

Located on the input to the discharge device 40 is a condenser 50 which is adapted to assume a charge dependent upon the presence or absence of a flame, in a manner that will be understood in the operation of the apparatus as explained. Connected between this condenser and the control electrode 42 is a resistor 52 which cooperates with a condenser 51 to form a filter network on the input of the discharge device 40. A resistor 53, connected between the control electrode 42 and cathode 43, is a conventional grid leak resistor. Located on the output of the discharge device 40 and on the input of the discharge device 45 is a resistor 54. A further resistor 55 is used in controlling the control electrode potential of the control electrode 47. Located in the output of the discharge device 45 is a control relay 58 comprising a relay winding 59, a pair of switch blades 60 and 61, the

latter of which are normally biased out of engagement with contacts 62 and 63, by means not shown. The switch blade 61 is normally biased into engagement with a contact 64. Connected in alternating current by-passing relation to the winding 59 is a condenser 65 which serves to filter out the alternating component of the current flowing in the output circuit of the discharge device 45.

The energization of the control burner is initiated by the electronic control circuits indicated generally by the numeral 70. The supplying of power to these circuits is by way of a transformer 71 having a primary winding 72 and a secondary winding 73. Included in these circuits are a pair of electron discharge devices 75 and 76 which may also be two sections of a dual triode tube. The discharge device 75 comprises an anode 77, a control electrode 78, and a cathode 79, the latter of which is adapted to be heated to be electron emissive by one of the filament heaters energized by the secondary 24. The discharge device 76 comprises an anode 80, a control electrode 81, and a cathode 82. Located in the output circuit of the discharge device 75 are a pair of series connected resistors 85 and 86. Connected between the junction of the two series resistors 85 and 86 is a further resistor 87 which may be adjustable and this resistor is also connected to the control electrode 81 of the discharge device 76. Connected between the control electrode 81 and cathode 82 is a timing condenser 88. A shunting resistor 89 is adapted to be connected in parallel with the condenser 88 by a reset switch 90. Located in the output of the discharge device 76 is a control relay 92 having a relay winding 93, and a pair of switch blades 94 and 95 which are normally biased, by means not shown, out of engagement with a pair of associated contacts 96 and 97 respectively. The condenser 98 is connected in alternating current bypassing relation to the winding 93 to by-pass the alternating component of the current flowing in the output circuit of the discharge device 76. A current limiting resistor 99 is provided in the energizing circuit of the subject apparatus.

Operation

In considering the operation of the present apparatus, it will be first assumed that the apparatus is completely shut down with the thermostatic device 10 not indicating the need for operation of the burner. Under this condition the solenoid valves 12 and 14 will be in a closed position and the ignition device 13 will be deenergized. Further, the control relays 92 and 58 will be in the deenergized position. The relay 92 will be in the deenergized position inasmuch as there is no power applied to the transformer 71 when the room thermostat 10 is open.

The reason the relay 58 will be in the deenergized position will be understood upon a brief consideration of the operation of the flame detection portion of the apparatus. For a complete understanding of the operation of the apparatus, reference should be made to a copending application of Richard S. Fiegal, Serial No. 730,649 filed February 24, 1947, now Patent Number 2,556,961. Briefly, the present flame detector is so arranged that it utilizes the rectifying characteristics of a flame in the controlling of an electronic circuit. When there is no flame appearing at either the pilot nozzle 15 or the main burner 11, there will be no rectification in a flame circuit that may be traced from the tap 26

4

10 through condenser 50, conductor 101, flame rod 16, the gap between 16 and the burners 11 and 15 which are grounded at 102, ground 103, and conductor 104 back to the lower terminal of secondary 25. If there is no flame present across the gap described above, there will be no direct current charge built up on the condenser 50 which is in the flame circuit traced. With no charge on the condenser 50, the control electrode 42 of the discharge device 40 will assume the same potential as the cathode 43 and therefore the discharge device will be conducting current on the alternating current half cycles of the power supply when the anode 41 is positive. The current flow may be traced from the tap 26 15 through conductor 105, resistor 54, conductor 106, anode 41, cathode 43, and conductor 104 back to the lower terminal of secondary 25. It will be noted that the last traced current flow 20 was through the resistor 54 and with this current flowing the voltage drop across this resistor will be such that the upper terminal will be negative and the lower terminal will be positive. Inasmuch as the control electrode 47 is connected 25 to the upper terminal of resistor 54 and the cathode 48 is connected to the lower terminal thereof, there will be a biasing voltage applied to the input of the discharge device 45 which will maintain the current flow in this discharge device 30 below the value necessary to effect energization of the relay 58. Thus, with no flame present, the relay 58 will be deenergized.

If a flame should be present at the pilot nozzle 15 or at the main burner 11, there will be a current flow in the flame circuit that was traced above and the conventional current flow will be greater in the direction traced so that the condenser 50 will assume a charge such that the upper terminal is positive and its lower terminal is negative. With this charge on the condenser 50, a biasing voltage will be applied to the input of the discharge device 40 so that this device will have its control electrode 42 negative with respect to the cathode 43 and the device will no longer be conducting sufficiently to maintain the discharge device 45 nonconductive. With the discharge device 45 conductive, the relay 58 will move to the energized position to indicate the presence of a flame at either the pilot nozzle or the main burner. The current flow circuit for the discharge device 45 may be traced from the upper terminal of the secondary 25 through conductor 107, relay winding 59, conductor 108, anode 46, cathode 48, and conductor 105 to the tap 26 of secondary 25. With sufficient current flowing in the last traced circuit, the relay 58 should become energized. Inasmuch as the operation of the flame detector depends upon the rectifying characteristics of a flame, it will be obvious that the apparatus will not detect the presence of flame if the electrode 16 should become grounded on the burner 11 or on the pilot nozzle 15 or if the flame gap should become bridged by a non-rectifying impedance. This is one of the added features of safety of the present apparatus. Thus, only when there is a rectifying impedance across the flame gap will it be possible for the relay 58 to become energized.

As soon as the space wherein the thermostatic device 10 is located begins to cool, the thermostatic device 10 will close its switching circuit and will connect the primary winding 72 in energizing relation to the secondary winding 24 so that power may be supplied to the circuit 70. This energizing circuit may be traced from

the lower terminal of secondary 24 through conductor 110, thermostatic device 10, conductor 111, conductor 112, primary 72, and conductors 113 and 114 to the upper terminal of secondary 24. As pointed out above, the voltage on the secondary 24 is relatively low and is used for supplying the energizing voltages for the filaments 31 to 34. Inasmuch as this voltage is low it is possible to use an ordinary thermostat circuit of the low voltage type which does not require the special installation requirements normally present in thermostat circuits that operate at high voltages.

With the primary 72 energized, a voltage will appear on the secondary 73 and this voltage will be sufficient to cause energization of the control relay 92 as the discharge device 76 will be initially conducting. The conducting circuit may be traced from the upper terminal of secondary 73 through conductors 115 and 116, winding 93, anode 89, cathode 82, and conductor 117 to the lower terminal of secondary 73. The discharge device 76 will be conducting because initially the control electrode 81 will be at the same potential as the cathode 82 because of a circuit that may be traced from the control electrode 81 through conductor 118, and resistors 87 and 86 to the cathode 82. Current will also flow through the discharge device 76 in a circuit that may be traced from the lower terminal of secondary 73 through conductor 117, resistors 86 and 85, anode 77, cathode 79, and conductor 115 to the upper terminal of secondary 73. While initially there is current flowing in this last traced circuit upon the closure of the thermostatic device 10, the voltage drop from the resistors 85 and 86 will have no effect upon the potential of the control 81 because of the fact the condenser 88 is connected between the control electrode 81 and cathode 82 and must assume a charge before the current flow in the discharge device 76 will be appreciably affected.

As soon as the relay 92 has become energized, the switch blades 94 and 95 will move into engagement with their associated contacts 96 and 97 respectively. When the blade 95 engages contact 97, an energizing circuit may be traced to the pilot solenoid valve 12 and ignition transformer 13 from the input power line 20 through conductor 120, switch blade 95, switch contact 97, conductor 121, junction 122, conductor 123, solenoid valve 12, and conductor 124 to the other input power line 21. The circuit to the ignition transformer is the same as that for the pilot valve 12 up to the junction 122 where the circuit is traced through the switch blade 61, switch contact 64, conductor 125, ignition transformer 13, and conductor 124 back to the other input power line 21. With the solenoid valve 12 energized and ignition transformer 13 energized, gas will flow to the pilot nozzle 15 and be ignited by the ignition transformer 13. The resultant pilot flame will bridge the gap between the nozzle 15 and the flame electrode 16 so that flame will be detected by the flame detector, in the manner explained above.

As soon as flame is detected at the pilot burner, the relay 58 will become energized and the switch blades 60 and 61 will move into engagement with their associated contacts 62 and 63 respectively. When the blade 61 engages contact 63 an energizing circuit is completed to the main solenoid 14 and this circuit may be traced from the input power line 20 through conductor 120, switch blade 95, switch contact 97, conductor 121, junc-

tion 122, blade 61, contact 63, conductor 126, solenoid valve 14, and conductor 124 back to the other input power line 21. With the solenoid valve 14 energized, gas will be supplied to the main burner 11. When the blade 61 moves out of engagement with contact 64 and into engagement with 63, the circuit to the ignition transformer is broken so that now only the pilot solenoid valve 12 and the main solenoid valve 14 are energized.

When the relay 58 becomes energized, and the blade 60 moves into engagement with contact 62, the control electrode 81 of the discharge device 76 is connected to the cathode 82 in a circuit that may be traced from the control electrode 81 through conductor 118, conductor 130, switch blade 60, switch contact 62, conductors 131, and 132, contact 96, switch blade 94, ground 133, ground 134, conductor 110, thermostatic device 10, and conductors 111 and 117 to the cathode 82. With this connection, the condenser 88 is shorted out and it is insured that the discharge device 76 will remain in the conducting condition so that the relay 92 will remain energized.

The apparatus will remain in the energized condition until such time as the thermostatic device 10 no longer indicates a need for burner operation. When there is no longer a need for burner operation, the thermostatic device 10 will open its circuit and the energizing circuit to the primary 72 of transformer 71 will be opened so that the power applied to the electronic control circuit 70 will be removed and the relay 92 will become deenergized, thus removing any source of charging voltage for condenser 88. When the relay becomes deenergized the switch blade 95 will move out of engagement with contact 97 and will open the energizing circuit to the pilot solenoid valve 12 and the main solenoid valve 14 so that the pilot burner and the main burner will be shut down. As soon as the flame disappears from the pilot burner and the main burner, there will no longer be a flame impinging upon the flame electrode 16 and the flame detector will no longer indicate the presence of flame so that the relay 58 will also move to the deenergized position to again assume the position shown upon the drawing.

Operation upon a failure of combustion

In the operation considered thus far, it has been assumed that the entire apparatus has been functioning properly and flame has been present when operation of the burner has been desired. Considering now the functioning of the apparatus in the event there should be a failure to initiate combustion or a failure of combustion after it has once been established, it is desired that the apparatus be rendered inoperative within a predetermined time after the apparatus indicates a combustion failure. Upon the energization of the electronic control circuit 70 by the closing of the thermostatic device 10, and energization of control relay 92, there should be a flame appearing at the pilot nozzle 15 upon the energization of the pilot solenoid 12 and the ignition transformer 13 by the relay 92. If no flame appears on the pilot nozzle 15 the relay 58 will remain in the deenergized position. It will thus be noted that the timing condenser 88 will begin to assume a charge which is directly proportional to the voltage existing across the resistor 86 in the output circuit of the discharge device 76. The time that it will take for this condenser 88 to assume the full voltage on the

resistor 86 will be dependent upon the size of the condenser 88 and that of the resistor 87 which is connected in series with the charging circuit of the condenser 88. If a flame is not detected within the predetermined time, determined by the time constant of the resistor 87 and condenser 88, the control electrode 81 will be biased negative with respect to the cathode 82 and the current flow in the discharge device 76 will drop below the point necessary to maintain the control relay 92 energized. When the relay 92 becomes deenergized the pilot burner and the ignition device will be deenergized and will remain deenergized until such time as the condenser 88 is discharged. In order to discharge the condenser 88, it is but necessary to close the reset switch 90 which connects the resistor 89 directly in parallel with the condenser 88. This will discharge the condenser so that it will be again possible to reenergize the relay 92 upon 20 the current flow in the discharge device 76 rising to a predetermined level. As soon as a flame is established at the pilot burner, the condenser 88 is shorted out by the engaging of the switch blade 60 to the contact 62 which is in circuit with the blade 94 and the contact 96 in the circuit that was traced above in considering the normal operation of the apparatus.

If the apparatus has been energized and has been operating normally for a period and there is then a flame failure, it will be noted that the flame detection relay 58 will move to the deenergized position and the shunting circuit for the condenser 88 will be removed. When the relay 58 moves to the deenergized position, the deenergized circuit through the ignition transformer 13 is again completed to the switch blade 61 and contact 64. If a flame is not reinitiated by the energization of the ignition transformer 13, the condenser 88 will assume a charge in the aforementioned predetermined time and will bias the discharge device 76 below the current conducting point necessary to maintain the relay 92 energized. With the relay 92 deenergized, the entire apparatus will be shut down until such time as the reset switch 90 is depressed and the condenser 88 is discharged so that it is again possible for current to flow through the discharge device 76 to energize relay 92. Again, if upon the reenergization of the relay 92 there is a flame appearing at the pilot nozzle 15, flame will be detected and the relay 58 will become energized to again shunt out the condenser 88 to maintain the discharge device 76 in a conducting condition.

Operation upon false indication of flame

If for any reason the flame detection relay should remain in the energized position to thusly indicate the presence of a burner flame when in actuality the burner was not energized, it is desired that the apparatus be maintained inoperative to prevent energization of the relay 92 and the energization of either of the solenoid valves 12 or 14. If the relay 58 is in the energized position falsely indicating flame, the switch blade 60 will be engaging the contact 62. If the thermostatic device 10 subsequently closes, there will be applied to the discharge device 76 an alternating current bias voltage which is phased so that the control electrode 81 will be negative when the anode 80 has a positive half cycle applied thereto. This biasing circuit will be completed only upon the closing of the thermostatic device 10 and may be traced from the control 75

electrode 81 through conductor 118, conductor 130, switch blade 60, switch contact 62, conductor 131, resistor 99, conductor 113, to the upper terminal of primary 12. The lower terminal of primary 12 is directly connected by means of conductors 112 and 117 to cathode 82. When the alternating current on the upper terminal of the primary 12 is negatively phased, the upper terminal of the secondary 13, which is connected to the anode 80 of the discharge device 76, will be positively phased. It will thus be seen that it will be impossible for the discharge device 76 to become conductive upon the closing of the thermostatic device 10 as long as the switch blade 60 is engaging contact 62. As soon as the fault causing false operation of the relay 58 has been removed, it is possible to initiate operation of the burner in the normal manner.

Conclusion

In conclusion, it will be seen that there has been provided in the present invention a simple and reliable burner control that may be readily controlled by a low voltage switching circuit. Also provided is an improved type of quick acting arrangement for shutting down the apparatus in the event there is any flame failure or in the event there is a false indication of flame by the flame detection portion of the apparatus. While we have shown one particular embodiment of the invention, it is to be understood that it has been for illustrative purposes only and since many modifications can be made by one skilled in the art, we intend our invention to be limited solely by the scope of the appended claims.

We claim as our invention:

1. Apparatus for controlling a fuel burner, comprising in combination, a source of power comprising a transformer having a high and a low voltage secondary winding, an electronic flame detector connected to be energized by said high voltage secondary winding and comprising a plurality of discharge devices having input and output circuits and having filament heaters, the latter of which are connected to said low voltage secondary winding, an electronic control circuit for initiating operation of the fuel burner, a second transformer comprising a primary and secondary winding, means connecting said last named secondary winding to energize said control circuit, and circuit means adapted to be completed by low voltage switching means indicative of the need for burner operation for connecting said primary winding to be energized by said low voltage secondary winding.

2. Apparatus for controlling a fuel burner, comprising in combination, an electronic flame detector comprising an electronic control device, a source of power comprising a transformer having a primary winding, a first secondary winding whose voltage is greater than a voltage applied to said primary, and a second secondary winding whose voltage is less than the voltage applied to said primary, means connecting said first secondary winding to said control device, an electronic control circuit means for initiating burner operation, low voltage switching means indicative of the need for burner operation, and circuit means adapted to be completed by said switching means for connecting said control circuit means to said second secondary winding.

3. Apparatus for controlling a fuel burner, comprising in combination, an electronic flame detector comprising an electron discharge device having an anode-cathode circuit, a source of

power comprising a transformer having a primary winding, a first secondary winding whose voltage is greater than a voltage applied to said primary, and a second secondary winding whose voltage is less than the voltage applied to said primary, means connecting said first secondary winding to the anode-cathode circuit of said discharge device, an electronic control circuit means for initiating burner operation, a step-up transformer for supplying energy to said control circuit means, and circuit means adapted to be completed by a low voltage switching means indicative of the need for burner operation for connecting said step-up transformer to be energized by said second secondary winding so that the only voltage on said circuit means will be from said secondary winding.

4. Apparatus for controlling a fuel burner, comprising in combination, an electronic discharge device having an anode, cathode, control electrode, and cathode heater, a power transformer connected in energizing relation to said anode and cathode, a rectifying means connected to said transformer, an electrical time delay network having a chargeable element connected to said control electrode and to said rectifying means, said rectifying means when energized normally tending to charge said chargeable element to a polarity to effect nonconduction of said discharge device, a source of power, means permanently connecting said source to said cathode heater, relay means in circuit with said anode for initiating operation of the burner when said discharge device is conductive, circuit means adapted to be completed by means indicative of the need for burner operation for connecting said power transformer to said source, said discharge device when said circuit means is completed energizing said relay means for a predetermined length of time dependent upon the charging time of said chargeable element, burner operation responsive means rendering said chargeable element ineffective in said time delay network when said burner is operating properly, and means including said circuit means when completed for applying a biasing potential to said discharge device to render said device inoperative when said responsive means is indicating burner operation falsely.

5. Apparatus for controlling a fuel burner, comprising, a source of power comprising a transformer having a pair of secondary windings, an electronic flame detector connected to be energized by one of said secondary windings and comprising a first electron discharge device having a filament heater, the latter of which is connected to the other of said secondary windings, an electronic control circuit means for initiating operation of the fuel burner including a second electron discharge device having a control electrode, circuit means adapted to be completed by means indicative of the need for burner operation for connecting said control circuit to be energized by the second of said secondary windings, and means including said flame detector for connecting said other secondary to the control electrode of said second electron discharge device to prevent the initiation of operation of the fuel burner when said flame detector is falsely indicating proper burner operation.

6. Apparatus for controlling a fuel burner, comprising in combination, a source of power comprising a transformer having a first secondary winding and a second low voltage secondary winding, an electronic flame detector con-

nected to be energized by the first of said secondary windings, an electronic circuit means for initiating operation of the fuel burner, a second transformer for supplying energy to said last named circuit means, and further circuit means adapted to be completed by a low voltage switching means indicative of the need for burner operation for connecting said second transformer to the second of said secondary windings.

7. Apparatus for controlling a fuel burner, comprising in combination, a first electronic circuit means including an electron discharge device having a control electrode, first relay means connected to and controlled by said discharge device, a source of power, control circuit means adapted to be completed by means indicative of the need for operation of the burner, said circuit means connecting said first electronic circuit means to said source when said circuit is completed by said indicative means, a second electronic circuit means for indicating proper operation of the burner, second relay means connected to and controlled by said second circuit means, means including said second relay means connected to the control electrode of said discharge device for maintaining said discharge device inoperative when said second relay is in operating position and said indicative means is subsequently actuated, a source of direct current controlled by said indicative means, and circuit means including time delay means connecting said direct current source to the control electrode of said discharge device for rendering said discharge device ineffective after a predetermined time delay when said second electrical circuit means does not indicate proper burner operation, said source of direct current being rendered inoperative when said control circuit means is not completed by said indicative means.

40 8. Apparatus for controlling a fuel burner, comprising in combination, a source of power comprising a transformer having a first secondary winding and a second low voltage secondary winding, an electronic flame detector connected to be energized by said first secondary winding and comprising a plurality of discharge devices each having an input and output circuit, filament heaters for said discharge devices which are connected to said second secondary winding, an electronic control circuit means for initiating operation of the fuel burner, and circuit means adapted to be completed by means indicative of the need for burner operation for connecting said control circuit means to be energized by said second low voltage secondary winding.

55 9. Apparatus for controlling a fuel burner, comprising in combination, a source of power comprising a transformer having a first secondary winding and a second low voltage secondary winding, an electronic flame detector connected to be energized by the first of said secondary windings and comprising a plurality of discharge devices having input and output circuits and having filament heaters, the latter of which are connected to the second of said secondary windings, an electronic control circuit means for initiating operation of the fuel burner, a second transformer comprising a primary and secondary winding, means connecting said last named secondary winding to energize said control circuit means, and circuit means adapted to be completed by means indicative of the need for burner operation for connecting said primary winding to be energized by said second low voltage secondary winding.

10. Condition control apparatus, comprising in combination, first means for initiating operation of condition changing means, said means comprising an electron discharge device having a heater therefor, a source of power, means continuously connecting only said heater to said source of power, first circuit means adapted to be completed by means indicative of the need for operation of the condition changing means, a power transformer, means including said first 10 circuit means connecting said discharge device to said source through said power transformer, a source of varying biasing voltage from said transformer, second circuit means connecting said source of varying biasing voltage in controlling 15 relation to said discharge device and adapted to be effective to render said discharge device inoperative only upon the completion of said first circuit means, relay means responsive to the proper operation of said condition changing 20 means for altering said second circuit means to thereby render said source of varying biasing voltage ineffective to control said discharge de-

vice upon said condition changing means operating properly, means independent of said transformer for energizing said relay means under control of said condition changing means, and 5 means including said first circuit means when completed for applying a second biasing voltage to said discharge device to render said device inoperative when said relay means is falsely indicating proper operation of said condition changing means.
